UNITED STATES PATENT OFFICE.

JOSEPH SOLATINOW, OF PASSAIC, NEW JERSEY.

SAFETY-STIRRUP.

No. 918,212.

Specification of Letters Patent.

Patented April 13, 1909.

Application filed October 18, 1908. Serial No. 457,988.

To all whom it may concern:

Be it known that I, JOSEPH SOLATINOW, a citizen of the United States of America, residing in Passaic, in the county of Passaic 5 and State of New Jersey, have invented certain new and useful Improvements in Safety-Stirrups, of which the following is a specification.

This invention relates to an improved 10 safety-stirrup by which the stirrup-strap becomes readily detached from the saddle in case the rider is thrown from the horse, so that the dragging along of the rider on the ground and the danger to life and limb 15 is prevented; and the invention consists in a safety-stirrup the strap of which is connected by a bail having a roller at its apex with a stationary keeper attached to the saddle, said keeper being provided with a 20 hinged and spring-actuated end-piece that is forcibly opened by the roller for permitting the detaching of the stirrup-strap and stirrup from the saddle in case of accident to the rider as will appear from the following 25 description and claims.

In the accompanying drawings, Figure 1 represents a side-elevation of my improved safety-stirrup, showing the connection of the stirrup-strap with the saddle, Fig. 2 is a 30 side-elevation of the strap-connection with the saddle, shown in the act of being detached in case of accident to the rider, Fig. 3 is an end-elevation of the connection of the stirrup-strap with the keeper on the 35 saddle, and Fig. 4 is a vertical transverse section of the stirrup-strap and keeper, on line 4, 4, Fig. 1; Figs. 3 and 4 being drawn on a larger scale.

Similar letters of reference indicate corresponding parts throughout the several 40 figures.

Referring to the drawings, *a* represents a portion of the saddle, *b* the stirrup and *d* the stirrup-strap. The stirrup-strap *d* is 45 provided with the usual tongue and buckle for adjusting the same to the desired length. To the upper end of the stirrup-strap is applied a bail *e*, of approximately triangular shape, the sides of which are bent sidewise 50 of each other and provided with eyes *e*¹ at their upper ends for receiving a fixed pivot-pin *e*². A grooved roller *f* is placed on the pin and adapted to turn on the same. The bail *e* is passed through the loop of the 55 stirrup-strap and its ends are so located

with respect to each other that the pivot-pin *e*² is located perpendicular to the plane of the strap, so that the roller *f* mounted on said pivot-pin rotates in said plane.

The roller *f* is supported on the lower part 60 of an oblong keeper *f*¹ of wrought iron or other suitable metal; the upper thicker part of the keeper *f*¹ is attached by rivets *f*² to the side-portion of the saddle, one at each side of the same. The keeper is in the form of 65 an oblong or rectangular frame attached at its upper part to the saddle in the manner indicated and spaced from the saddle at its lower part, as shown in Fig. 4, so as to form a track for the roller *f* upon which the latter may travel lengthwise of the saddle.

The roller *f* travels only in contact with the track formed by the lower part of the oblong keeper and said roller is held on said track by the bail, the side-portions or legs of which 70 pass downwardly from the roller opposite sides of the track, so that the latter is straddled from beneath by the bail. The rear-end of the keeper *f*¹ is formed of a hinged and spring-actuated closing-piece *f*³, which 75 is held normally in position against the upper bar of the frame by a flat spring *f*⁴ of considerable strength, which presses on the end of the lower portion of the keeper, the end being reduced in width so as to permit 80 the pivoting of the forked end of the closing-piece *f*³ thereto.

When the stirrup is used in the usual manner, it is suspended by its strap bail and the roller from the stationary keeper, at the 90 side-portion of the saddle. In case the rider is thrown to the ground and his foot caught in the stirrup, the strain of the foot on the stirrup-strap moves the roller with the bail toward the pivoted and spring-actuated 95 end-piece of the keeper and moves the same by the strain exerted thereon against the tension of the spring, into line with the lower portion of the keeper, as shown in dotted lines in Fig. 1 and in full lines in 100 Fig. 2, so as to permit the detaching of the roller and bail from the keeper, and thereby the disconnection of the stirrup-strap and stirrup from the saddle, so that the danger 105 of the rider being carried along and dragged over the ground by the entanglement with the stirrup is prevented.

My improved safety-stirrup is of great advantage for the riders in maneuvers, races and hunting, as it forms a protection

against serious accidents in case the rider is thrown from the horse, and dragged along by the same.

Having thus described my invention, I claim as new and desire to secure by Letters Patent:

1. In a safety-stirrup, the combination of a track fixed to the saddle but spaced from the same, a roller movable on said track, a bail which straddles said track from beneath and between the ends of which the roller is journaled, and a stirrup-strap supported by said bail.

2. In a safety-stirrup, the combination of an oblong open keeper connected at its upper portion only with the saddle and having at its lower portion a track spaced from the latter, a grooved roller traveling solely on said track within the open part of the keeper, a pin on which the roller rotates, a bail connected at its ends with the ends of said pin and passing downwardly at opposite sides of the track, and a stirrup-strap carried by said bail.

3. In a safety-stirrup, the combination of a looped stirrup-strap, a bail passed through the loop of the strap, a pin connecting the ends of the bail and located perpendicularly to the plane of the strap, and a roller on said pin.

4. In a safety-stirrup, the combination of a track directed lengthwise of the saddle and spaced from the latter, a roller traveling on said track, a looped stirrup-strap, and a bail between the ends of which said roller is journaled and passing through the stirrup-strap, the side-portions or legs of the bail being so bent with relation to each other that said roller is disposed in the plane of the strap.

In testimony, that I claim the foregoing as my invention, I have signed my name in presence of two subscribing witnesses.

JOSEPH SOLATINOW.
